UNITED STATES PATENT OFFICE.

SPENCER HEATH, OF BALTIMORE, MARYLAND.

VARIABLE-PITCH PROPELLER.

Application filed July 2, 1919. Serial No. 308,112.

To all whom it may concern:

Be it known that I, SPENCER HEATH, a citizen of the United States, residing at Baltimore, State of Maryland, have invented 5 certain new and useful Improvements in Variable-Pitch Propellers, of which the following is a specification.

This invention relates to propellers, and more particularly to aerial propellers.

10 In certain classes of air work, it is extremely desirable to be able to vary the pitch or angle of the blades while the propeller is running, to compensate for different conditions of engine speed or atmospheric density. In other classes of work, such as in the control of dirigibles, and in checking the speed of air planes when landing on a comparatively restricted surface, as, for example, the deck of a ship, it becomes 15 important to completely reverse the propeller blades, so as to change the direction of thrust.

While it has heretofore been proposed to construct propellers so that the pitch of the 20 blades can be adjusted, the adjustment has, in most cases, been limited to a comparatively small angle. In prior devices, too, the adjusting mechanism has included parts constantly in frictional engagement, and the 25 high speed of the propeller has proven so destructive to the contact surfaces as to render such arrangements impractical.

The objects of the present invention, therefore, are to provide a propeller construction in which the blades can be completely adjusted or turned through 360° in either direction, and in which all parts between which there is relative movement are normally out of contact, being brought into 30 engagement only momentarily, at the time the adjustment takes place. To this end I have devised an improved arrangement of gearing by means of which rotation of the engine shaft in the same direction serves to 35 turn the blade adjusting mechanism in either direction, at will, such gearing including a reversing device, and also a worm and worm wheel, which latter serves to lock or hold the blades in adjusted position, and ab-

solutely prevent accidental displacement 50 thereof.

In order that my invention may be readily understood, reference is had to the accompanying drawings, forming part of this specification, and in which:—

Fig. 1 is an end elevation, partly in section, of my improved propeller hub and associated parts;

Fig. 2 is a view of the same, half in horizontal section and half in plan;

Figs. 3 and 4 are sections on the line X—X of Fig. 1 looking respectively to the right and the left; and

Figs. 5 and 6 are elevations showing my improved band brake mechanism in inoperative and operative positions, respectively.

Referring to the drawings in detail, my improved propeller comprises a hub 1, shown as cylindrical, and provided at its ends with a pair of tubular sockets adapted to receive the ends of the propeller blades, two such blades being shown. The hub is provided at its center with a transversely extending tapered socket 2 adapted to receive the engine shaft 3, to which the hub is secured by means of a nut 3^a. The socket member 2 is extended rearwardly as indicated at 4 in Fig. 2, for a purpose which will hereafter appear.

Each propeller blade 5 is received in a cylindrical ferrule 6, in which it is secured by means of wedges 7, the internal diameter of the ferrule being somewhat enlarged at its inner end for this purpose. The ferrules 6 are capable of rotation within the tubular sockets formed by the hub 1 and are held therein by means of anti-friction thrust bearings 9 interposed between the outer ends of the ferrules and retaining rings 8, which are screw-threaded to the ends of the hub.

In order to angularly adjust or rotate the ferrules and blades upon their own axes, I secure an annular internal gear 10 in the inner end of each ferrule. Meshing with this annular gear are a pair of diametrically opposed pinions 11 secured to stub shafts 12, journaled in a fixed annular frame

or ring 13, secured within the hub 1 as by means of screws 14.

Secured to the inner ends of the shafts 12 are a pair of worm wheels 15 having oppositely inclined teeth. Interposed between these worm wheels and meshing therewith is a worm 16, having crossed threads, as clearly shown in Figs. 2 and 4. One of the threads is adapted to engage with one 10 of the worm wheels and the other thread is adapted to engage the other worm wheel, the threads being of opposite pitch, so that when the worm revolves, the worm wheels will be driven in such a direction as to cause 15 the pinions 11 to turn the annular gear 10 in the same direction. It will be observed that this double thread is necessary, since as will be obvious, a worm with a single thread would drive the pinions 11 in such 20 a direction that they would tend to turn the annular gear 10 in opposite directions, thus resulting in an inoperative arrangement. By the use of my novel double threaded worm, the pinions are caused to rotate in 25 the proper directions.

The worm 16 is secured to a shaft 17 extending transversely through the hub and journaled in bosses 18 carried by the ring 13. The rear ends of the shafts 17 project beyond the hub, and to the projecting end of each shaft are secured a pinion 19 and a sprocket wheel 20. Mounted between the pinions 19 and in mesh therewith is a gear 21, loosely journaled on the 35 extension 4 of the shaft socket 2. Rigidly connected with the gear 21 is a sleeve 24 carrying at its end a brake drum 26.

While I have shown the sleeve 24 as carried by and journaled on the hub extension 4, it will be understood that this 40 sleeve may be mounted upon the shaft 3 itself or other member rigid with the hub sockets 1 and rotatable therewith about the same axis. The essential thing is that the 45 sleeve 24 is wholly supported by such member and normally rotates with it, so that there is no constant running friction between any movable parts of the blade adjusting mechanism, and any fixed parts or 50 elements.

Freely journaled upon the sleeve 24 is a sprocket wheel 23, rigidly connected with a sleeve 25, carrying at its end a brake drum 27. A sprocket chain 22 passes around the 55 two sprockets 20 and the sprocket wheel 23, thus gearing them positively together.

From the foregoing it will be evident that 60 rotation of the gear 21 and the concentric sprocket wheel 23 in the same direction will turn the shafts 17 in opposite directions.

In other words, the gear 21 and its associated pinions 19, and the sprocket wheels 20 and 23 with their chain 22, constitute reverse gearing by means of which the shafts 65 17 may be rotated in either direction,

through the rotation of the engine shaft in one direction.

Co-operating with the brake drums 26 and 27, which rotate with the propeller, are relatively fixed brake bands 28 and 29. 70 These two bands have one end fixed, as, for example, by being secured to a pivot pin 30, set into an enclosing housing 35. The other ends 31 and 32 of the brake bands 28 and 29, respectively, are secured to pins 75 projecting from the opposite sides of a Y-shaped lever 33, mounted on the pivot pin 30 and provided with an operating handle 34. The housing 35 which carries the pivot pin 30 is suitably supported on a part 80 36 of the engine frame. The reversing gear above described is also enclosed within a case or housing 37, having a flange 38 shaped to fit the hub 1, and secured thereto.

Normally, with the lever 34 in the central or neutral position, as shown in Fig. 5 both brake bands 28 and 29 are out of contact with their respective drums, and are separated therefrom by a suitable clearance.

When the propeller is running, therefore, 90 there are no parts in frictional contact, and hence no excessive wear. When it is desired to angularly adjust or turn the propeller blades on their axes, the lever 34 is thrown to one side or the other, as indicated in Fig. 6, thus tightening one or the other of the brake bands and causing it to engage its respective drum.

Since the engine shaft and propeller are rotating, it will be evident that as soon as the friction 100 between a brake band and its drum is sufficient to retard the free movement of the drum, the drum will be caused to slow up relative to the propeller, with the result that either the gear 21 or the sprocket wheel 23 is caused to rotate relative to the propeller hub, thus driving the shafts 17 in one direction or the other according to the direction in which the lever 34 was thrown. In other words, this lever selectively brings 105

into operation, either one drum or the other, according to which way it is thrown, and thus drives the shafts 17 through either the gearing or the sprocket wheels, thereby producing angular displacement of the propeller blades in one direction or the other, as desired.

It will be particularly observed that with my improved construction there is no limit to the amount of rotation which may be 120 imparted to the propeller blades, the extent of turning being simply dependent upon the length of time that the brake band is held in engagement with its drum. Owing to the reduction gearing between the drums and blades, such gearing including the worm 16, a number of revolutions of the shafts 17 is necessary in order to produce a comparatively small displacement of the blades. Furthermore it will be observed that by the 130

simple expedient of using the worm and worm wheels, I secure a positive lock, for effectively holding the blades in adjusted position and preventing accidental displacement. By employing two worm wheels and two pinions arranged on opposite sides of the axes of rotation, I produce a balanced couple and thus avoid danger of cramping or binding, such as might result from the application of power to one point only of the annular gear 10.

What I claim is:—

1. The combination with a propeller having a hub, and angularly adjustable blades mounted therein, of means for angularly adjusting the blades comprising an element supported directly on and wholly by said hub and rotatable therewith, a relatively fixed element normally out of contact with said hub-carried element, and means for bringing said elements into operative engagement when it is desired to actuate said adjusting means.

2. The combination with a propeller having hub sockets, of blades having shanks angularly adjustable in said sockets, and means for angularly adjusting said blades, said means comprising a rotary element supported wholly on a member rigid with said hub sockets and rotatable therewith about the same axis, a relatively fixed element normally out of contact with said rotary element, and means for bringing said fixed and rotary elements into engagement to actuate said adjusting means.

3. The combination with a propeller having angularly adjustable blades, of mechanism for adjusting said blades in either direction while the propeller is running, said mechanism comprising stationary and rotary elements normally out of contact, and means, controllable at will, for bringing said elements into engagement to actuate said adjusting mechanism.

4. The combination with a propeller having angularly adjustable blades, of mechanism for adjusting said blades in either direction while the propeller is running, said mechanism comprising a pair of elements rotating with the propeller, relatively stationary manually controlled means normally out of contact with said rotary elements, and means for selectively bringing said manually controlled means into engagement with one or the other of said rotary elements to actuate said adjusting mechanism as desired.

5. A propeller having angularly adjustable blades, a power shaft on which said propeller is mounted and means for adjusting said blades while the propeller is in motion, such means comprising gearing carried by the propeller hub, and means controlled at will, and operable wholly by the rotation of said power shaft, for rotating said gearing in either direction.

6. The combination with a propeller having angularly adjustable blades, of a power shaft on which said propeller is mounted, and mechanism operable wholly by the rotation of said power shaft in the same direction for adjusting said blades in either direction, said mechanism comprising stationary and rotary elements normally out of contact, and means controllable at will, for bringing said elements into engagement to actuate said adjusting mechanism.

7. The combination with a propeller having angularly adjustable blades, of a power shaft on which said propeller is mounted, and mechanism operable wholly by the rotation of said power shaft in the same direction for adjusting said blades in either direction, said mechanism comprising a pair of stationary elements and a pair of elements rotating with the power shaft, said stationary and rotary elements being normally out of contact, and means controllable at will, for selectively bringing one of said stationary and rotary elements into engagement to actuate said adjusting mechanism.

8. The combination with a propeller having angularly adjustable blades, of a power shaft on which said propeller is mounted, and mechanism operable wholly by the rotation of said power shaft in the same direction for adjusting said blades in either direction, said mechanism comprising a pair of elements rotating with the power shaft, and manually controlled relatively stationary means for selectively engaging and retarding one or the other of said rotary elements to actuate said adjusting mechanism, said rotary and relatively stationary means being normally out of contact.

9. A propeller having angularly adjustable blades, and means for adjusting the same while the propeller is in motion, such means comprising gearing carried by the propeller hub, and means controllable at will and operable by rotation of the engine shaft for driving said gearing in either direction.

10. A propeller having angularly adjustable blades, a power shaft on which the propeller hub is mounted, and means for adjusting said blades while the propeller is in motion, such means comprising gearing carried by said propeller hub, and mechanism controllable at will and operable by rotation of the power shaft for driving said gearing in either direction.

11. A propeller having angularly adjustable blades, and means for adjusting the same while the propeller is in motion, such means comprising gearing carried by the propeller hub, and means for causing the rotation of the engine shaft in one direction to drive said gearing in either direction.

12. A propeller having blades completely

- rotatable about their own axes, and means for completely rotating the blades at will in either direction from any given position while the propeller is revolving continuously in the same direction.
13. A propeller having blades rotatable through at least 180° about their own axes, a power shaft on which said propeller is mounted, and mechanism operable by said power shaft for rotating the blades while the propeller is in motion to reverse the effect thereof, said mechanism comprising manually movable means normally out of contact with the blade rotating means.
14. A propeller having at the base of each blade means for rotating the blade on its own axis, a uni-directional rotary source of power, and controllable means, including said source of power and reversing gearing, for operating said rotating means in either direction.
15. A propeller having angularly adjustable blades, and means for adjusting them, said means comprising reversing gearing including a chain and sprocket wheels, and a uni-directional rotary source of power for operating said reversing gearing.
16. A propeller having angularly adjustable blades, means associated with each blade for angularly adjusting the same, a pair of elements rotating with the propeller and operatively connected through reverse gearing with said adjusting means, and a pair of non-rotary devices adapted to selectively engage said rotating elements to actuate the adjusting means in either direction.
17. A propeller having angularly adjustable blades, means associated with each blade for angularly adjusting the same, relatively fixed elements and elements normally rotating with the propeller and operatively connected with said adjusting means, all of said rotating elements being normally entirely out of contact with all fixed elements, whereby running friction is avoided, and means for bringing one of said relatively fixed elements into operative engagement with one of said rotating elements, when desired, to actuate said adjusting means.
18. A propeller having angularly adjustable blades, means associated with each blade for angularly adjusting the same, a pair of brake drums normally rotating with the propeller, and operatively connected through reverse gearing with said adjusting means, and a pair of brakes adapted to selectively engage said rotating drums to actuate the adjusting means in either direction.
19. A propeller having angularly adjustable blades, means associated with each blade for angularly adjusting the same, a pair of brake drums normally rotating with the propeller, and operatively connected through reverse gearing with said adjusting means, a pair of brakes adapted to engage said rotating drums to actuate the adjusting means in either direction, and a single lever for selectively shifting said brakes.
20. A propeller having angularly adjustable blades, means associated with each blade for angularly adjusting the same, a pair of brake drums normally rotating with the propeller, and operatively connected through reverse gearing with said adjusting means, a pair of brakes adapted to engage said rotating drums, to actuate the adjusting means in either direction, and lever means for selectively shifting said brakes.
21. The combination with a hub, of a propeller blade mounted therein for rotation on its own axis, and gearing for so rotating said blade, said gearing including a pair of worms having right and left threads mounted on the same axis, and a pair of oppositely disposed worm wheels meshing with said worms.
22. The combination with a hub, of a propeller blade mounted therein for rotation on its own axis, gearing located inside the hub and extending outside thereof and mechanical means normally out of contact with said gearing but adapted to be brought into engagement with such extending portion for rotating said blade, said gearing including a worm and worm wheel, serving to hold the blade in adjusted position.
23. The combination with a hub, of a propeller blade mounted therein for rotation on its own axis, and gearing for rotating said blade, said gearing including a worm having crossed threads, and a pair of oppositely disposed worm wheels meshing therewith.
24. The combination with a hub, of a propeller blade mounted therein for rotation on its own axis, and gearing for rotating said blade, said gearing comprising an internal annular gear secured to said blade, a pinion meshing therewith, a worm wheel rigid with said pinion, and a worm engaging said worm wheel.
25. The combination with a hub, of a propeller blade mounted therein for rotation on its own axis, and gearing for rotating said blade, said gearing comprising an internal annular gear secured to said blade, a pair of pinions meshing therewith, a worm wheel rigid with each pinion, and a worm having crossed threads disposed between and meshing with said worm wheels.
26. The combination with a hub, of a propeller blade mounted therein for rotation on its own axis, and gearing for rotating said blade, said gearing comprising an annular gear, a pair of pinions meshing therewith, a pair of worm wheels respectively secured to said pinions, and a worm having crossed threads disposed between said wheels and

meshing therewith, one of said wheels engaging one thread, and one the other thread.

27. A propeller having a hub, a rotating member to which said hub is rigidly secured, 5 adjustable blades carried by said hub, means for adjusting said blades comprising an element supported directly on and wholly by said member and rotatable therewith, a rel-

atively fixed element normally out of contact with said first named element, and means 10 for bringing said elements into operative engagement when desired to actuate said adjusting means.

In testimony whereof I affix my signature.

SPENCER HEATH.
